UNITED STATES PATENT OFFICE.

PETER ECKMAN, OF SYRACUSE, KANSAS.

CARPET-FASTENER.

SPECIFICATION forming part of Letters Patent No. 520,096, dated December 4, 1894.

Application filed December 19, 1893. Serial No. 494,041. (No model.)

To all whom it may concern:

Be it known that I, PETER ECKMAN, of Syracuse, in the county of Hamilton, State of Kansas, have invented certain new and useful 5 Improvements in Carpet-Fasteners, of which the following is a specification, reference being had to the accompanying drawings.

The object of my invention is to produce an improved device for holding a carpet 10 firmly and smoothly against a floor without the use of tacks, or any such thing calculated to deface a polished floor.

In the accompanying drawings: Figure 1 is a plan view of my rug holder complete. 15 Fig. 2 shows a modified form of brace for the same. Fig. 3 is a sectional view of one of the side plates. Fig. 4 illustrates the method of fastening the preferred form of spring-retaining clips to the side plate.

Referring to the figures on the drawings: 20 1 indicates the inclined base or side plate of a frame made, in practice, of a size to hold a rug for which it is adapted. It may be provided with diagonal braces 2, as shown in Fig. 1, or with braces 3 extending, for example, from a baseboard of a room. In practice, however, the former method is preferred, 25 since the braces would then be covered by the carpet. In the latter it would be necessary to adopt some other means of obscuring them as much as possible. Each side plate is preferably made as shown in Fig. 3 of the drawings, in which a beveled base-plate is adapted to be set under the edge of the carpet to be retained and a curved or beveled 30 guard plate rising at its highest part a little above the surface of the carpet and sloping easily to the floor. The side plates may be

made of any suitable material as for example, wood, or preferably hard rubber, or gutta 40 percha.

5 indicates a spring-retaining clip preferably made of wire and bent to form a coiled spring in its middle part. Its lower end 7 is inserted in the base-plate and securely united 45 to it. The other end is bent to form a hook 8 pressed by the operation of the coiled spring against the top of the base-plate. The coiled spring is, in practice, set into a recess 9 at the juncture of the base-plate and guard plate. 50

In practice, the edge of the carpet is laid upon the base-plate and the hooked or bent end is inserted through the fiber of the carpet, in which it is securely retained by the action of the coiled spring. The middle of 55 the hook is completely embedded in the pile of the carpet and is obscured from sight. The guard plates serve to protect the spring clip from being bent when stepped upon and also form an ornamental finish for the edge of 60 the carpet.

What I claim is—

In a rug holder, the combination with a frame composed of strips consisting of a base plate and an elevated guard plate gradually 65 downwardly curved to the floor, of spring clips secured to the guard plates adapted to clamp the rug to the base plates and to be protected by said guard plates, substantially as specified. 70

In testimony of all which I have hereunto subscribed my name.

PETER ECKMAN.
